FIGURE 1 is a perspective view of my combined heating and massaging unit showing my new design;

FIGURE 2 is a top plan view of my combined heating and massaging unit and particularly showing the heater surface thereof;

FIGURE 3 is an elevational view of one side thereof, the elevational view of the other side being substantially the same;

FIGURE 4 is a front end view thereof;

FIGURE 5 is a bottom plan view showing the massage portion of my combined heating and massaging unit; and

FIGURE 6 is a rear end view thereof.

The coiled wire hand strap member is fragmentarily shown in FIGS. 1 and 4 and has been omitted in FIG. 6 for ease of illustration.

I claim:

The ornamental design for a combined heating and massaging unit, substantially as shown and described.
